UNITED STATES PATENT OFFICE.

MILTON ROBERT WOOD, OF BROOKLYN, NEW YORK.

APPARATUS FOR DISTILLATION OF AMMONIACAL LIQUIDS.

SPECIFICATION forming part of Letters Patent No. 415,133, dated November 12, 1889.

Application filed March 2, 1889. Serial No. 301,742. (No model.)

To all whom it may concern:

Be it known that I, MILTON ROBERT WOOD, of the city of Brooklyn, county of Kings, State of New York, have invented a certain new and useful Improvement in Apparatus for Distillation of Ammoniacal Liquids to Obtain Ammoniacal Gas or Aqua-Ammonia, of which the following is a specification.

The apparatus herein described is equally efficacious in the distillation of liquors weak in ammonia with those that are strong. It is so constructed and operated that the distillation is carried on both with the use of a decomposing reagent and without. It is especially adapted for the distillation of the ammoniacal liquors produced by the so-called "ammonia-soda method," and to be operated in connection with the apparatus patented by me. (See United States Patents of March 20, 1888, No. 379,752, and June 19, 1888, No. 384,884.)

I will describe in detail an apparatus embodying my improvement and then point out the novel features in claims.

In the accompanying drawings, Figure 1 is a side elevation, partly broken away, of an apparatus embodying my improvement. Fig. 2 is a plan or top view of the same. Figs. 3 and 4 are plan and sectional views of certain trays employed in the apparatus, the section of Fig. 4 being taken on the line $x-x$, Fig. 3. Figs. 5 and 6 are plan and sectional views of certain baffle-plates employed, the section of Fig. 6 being taken on the line $y-y$, Fig. 5. Figs. 7 and 8 are plan and sectional views of certain other trays employed in the apparatus, the section of Fig. 8 being taken on the line $z-z$, Fig. 7. Figs. 9 and 10 are plan and sectional views of certain other baffle-plates employed, the section of Fig. 10 being taken on the line $w-w$, Fig. 9.

Similar letters of reference designate corresponding parts in all the figures.

A designates what I term the "primary still" of the apparatus. This still comprises a case or shell, which case or shell is divided transversely by a partition a , so as to form therein two chambers $A' A^2$. The upper of these chambers, or A' , is a refrigerator-chamber. The lower, or A^2 , is a heating-chamber. In the upper or refrigerator chamber A' are

arranged a number of vertically-extending pipes a' , through which ascending ammoniacal gases and vapors pass. After passing through said pipes the gases are received into a chamber A^3 at the upper extremity of the still, and are from thence conveyed away through an outlet a^2 . The chamber A^3 is separated from the chamber A' by a diaphragm a^3 . Refrigerating-liquid is introduced into the chamber A' through a pipe a^4 . The chamber A^2 of the still receives the ammoniacal liquor to be distilled. Such liquor enters in this instance through a pipe a^5 . From the pipe a^5 the liquor is discharged upon a shallow tray a^6 . An outlet for the liquor received upon the tray a^6 is afforded through vertically-extending pipes a^7 , which extend nearly but not quite to the top of the tray a^6 . It will be observed that the inner and downwardly-extending end of the inlet-pipe a^5 extends in this instance below the upper end of the outlet-pipe a^7 . The inner opening of the pipe a^5 is therefore always sealed by the liquor contained in the tray a^6 . From the tray a^6 the liquor passes into a tray a^8 . The tray a^8 is of less diameter than the interior of the chamber A^2 , and it is centered therein by lugs a^9 , extending horizontally therefrom at its circumference and contacting with the inner surface of the chamber. Between the tray a^6 and the tray a^8 is arranged a horizontally-extending baffle-plate a^{10} . The baffle-plate a^{10} is more clearly illustrated in Fig. 5. It is provided near its circumference with circumferentially-extending rows of perforations, but its central portion is solid. The ammoniacal liquor, passing through the pipes a^7 downwardly upon the tray a^8 , passes from the latter tray through pipes n , when the tray a^8 is full enough, and thence downwardly upon another tray a^6 . Below the tray a^8 is a baffle-plate a^{11} , which baffle-plate is illustrated more clearly in Fig. 9. This baffle-plate is provided about centrally with a number of perforations, but its outer or circumferential portion is solid.

I have now described one set of the trays and baffle-plates employed. I have illustrated a number of such sets of trays and baffle-plates, the construction of all being the same, and I wish it to be understood that I may em-

ploy any desired number of such trays and baffle-plates. It will be seen that the pipes a^7 and n extend far enough into the trays a^8 a^6 to form seals at the lower ends of the pipes 5 when the trays a^8 are filled with liquor.

The liquor passes downwardly through the trays until it reaches the lower portion of the chamber A^2 . From thence it is conveyed through an outlet-pipe B into a secondary 10 still or secondary stills B^2 . I have shown two such stills. In the secondary still or stills B^2 the ammoniacal liquor is heated, and is freed from its acid radical preferably by the use 15 of a hydroxide of an alkali or an alkaline earth. In order to heat the liquor, I have shown in dotted outline in Fig. 2 steam-coils C . These coils are perforated and steam is admitted to them through inlet-pipes b and is forced freely through the liquor contained 20 in the secondary stills. During this operation I prefer to agitate the liquor being treated, and I have shown rotary agitators D arranged in said stills, which agitators are mounted on shafts d , deriving rotary motion 25 from pulleys d' , which may be driven in any suitable manner. The hot vapor and gases from the secondary stills B^2 pass to a pipe B^3 , and thence into the primary still A beneath the lowest of the baffle-plates. They then 30 pass upwardly through the perforations in the baffle-plates and through central openings in the trays a^6 , passing in and out through the baffle-plates, the trays a^6 , and around the edges of the trays a^8 , so that they pursue a 35 constant sinuous course in passing upwardly. Being hot they heat the ammoniacal liquors contained in the trays and carry along in their passage a considerable quantity of ammoniacal gas from the chamber A^2 . The 40 vapor and gases pass upwardly through the pipes a^8 in the refrigerating-chamber, where the vapor is condensed, and from which it drops back upon the upper of the trays a^6 , to be again subjected to the same operation, as 45 before. The ammoniacal gases will pass off through the outlet-pipe a^2 .

I have shown the trays and baffle-plates as provided with inwardly-extending lugs g . These lugs, when all the trays and baffle-plates 50 are in position in the still, operate to maintain the trays and baffle-plates separated from each other. The tier of trays and baffle-plates is supported upon lugs or projections e , extending from the inner surface of the 55 chamber A^2 and below said tier.

I prefer that when the trays and baffle-plates are arranged in the chamber the lugs g shall occupy positions one above the other, as shown more clearly in Fig. 1.

I have shown a safety-valve H , of ordinary construction, arranged upon the chamber A^3 of the primary still. In this safety-valve 60 may be an oil-seal h , of ordinary construction.

Of course I do not wish to be understood as 65 limiting myself to the use of any specific number of secondary stills B^2 nor to the relative arrangement between the stills shown

and described, as, obviously, I may use any desired number of secondary stills, and they may be arranged in various relations to the 70 primary still.

Man-holes I may be arranged upon any of the stills, as shown more particularly in Fig. 1.

It is to be observed that in the upward passage of the ammoniacal gases and vapor they 75 heat the trays and consequently the liquor contained therein by radiation only, and do not come in contact with the liquor.

The cocks S S' in the pipes B^3 and B may be used to regulate the flow of liquor and 80 gases and vapor, as desired.

What I claim as my invention, and desire to secure by Letters Patent, is—

1. The combination, with a primary still, embracing a heating-chamber, of a number 85 of intercommunicating trays in said heating-chamber, a number of perforated baffle-plates interposed between said trays and a secondary still, a passage for liquor between said primary still and the secondary still, 90 and a passage for gas and vapor from said secondary still back to the primary still, substantially as specified.

2. The combination, with a primary still, embracing a heating-chamber and a refrigerating-chamber, of a number of intercommunicating trays in said heating-chamber, a number of perforated baffle-plates interposed between said trays, a secondary still, a passage for liquor between said primary still and the secondary still, and a passage for gas and vapor from said secondary still back to the primary still, substantially as specified. 95

3. The combination, with a primary still, embracing a heating-chamber, of a number 105 of trays in said heating-chamber, a number of perforated baffle-plates interposed between said trays, a secondary still, a passage for liquor between the primary still and the secondary still, a passage for gases and vapor 110 from said secondary still back to the primary still, an agitator in said secondary still, and heating apparatus also in said secondary still, substantially as specified.

4. The combination, with a primary still, 115 comprising a heating-chamber, a refrigerating-chamber, pipes extending through said refrigerating-chamber and communicating with the heating-chamber, and through which ammoniacal gas from the heating-chamber 120 will pass, trays and baffle-plates arranged in said heating-chamber, a secondary still, and passages for liquor and vapor and gases between said primary and secondary stills, substantially as specified.

5. The combination, with a primary still, of 125 trays arranged therein and provided with central openings, other trays arranged therein of less diameter than the interior of the still, pipes affording communication between said trays, baffle-plates arranged between said trays, certain of said baffle-plates having perforations near their circumferences, and certain other of the baffle-plates having

perforations near their centers, substantially as specified.

6. The combination, with a primary still, of trays arranged therein and provided with 5 central openings, other trays arranged therein of less diameter than the interior of the still, pipes affording communication between said trays and extending at their lower ends

below the upper edges of the trays beneath them, and baffle-plates arranged between said 10 trays, substantially as specified.

MILTON ROBERT WOOD.
